UNITED STATES PATENT OFFICE.

ALI MALEKH, OF NEW YORK, N. Y.

DRAFT-REGULATOR FOR SHIPS' GALLEYS.

SPECIFICATION forming part of Letters Patent No. 427,336, dated May 6, 1890.

Application filed November 21, 1889. Serial No. 331,085. (No model.)

To all whom it may concern:

Be it known that I, ALI MALEKH, of New York, in the county of New York and State of New York, have invented a new and Improved Draft-Regulator for Ships' Galleys, of which the following is a full, clear, and exact description.

The object of my invention is to provide means whereby a good draft may be secured in a ship's galley stove or range no matter what the direction of the wind or in what position the sails may be trimmed; and my invention consists of an air-deflector and support combined with the exposed part of the galley-pipe, the deflector being arranged to convert the back currents from the sails into a continuous draft, and also to catch the headway wind.

Reference is to be had to the accompanying drawings, forming a part of this specification, in which similar letters of reference indicate corresponding parts in all the figures.

Figure 1 is a plan view of a vessel, showing my invention applied to the galley-pipe on deck; and Fig. 2 is an enlarged detailed perspective view of the same.

A represents the exposed part of the galley-stove pipe, B the support, and C the deflector attached to the support. The support in this instance is a quadriod, and it may be secured to the pipe by a ring b, which surrounds the pipe, and the rods b', which connect the ring to the legs d of the quadriod. In case the sup-

port is of quite heavy material the ring and rods may be dispensed with. The deflector 35 is attached to the legs d of the support by staples f, which may be removed, so that the support may be attached to either leg of the quadriod, or it may be made permanent and the whole support adapted to be turned 40 for holding the deflector in the proper relative position with the pipe and the direction or currents of the wind. The deflector is held in a sloping position by the support, so that the upper edge nearly if not quite covers the top of the pipe, so that it deflects down-currents from the sail away from the pipe, which alone is sufficient to prevent smoking in the galley and to produce a fair draft. In case considerable draft is desirable the deflector will be set to catch the headway wind, or the wind pressing forward at the side of the mast opposite the trim of the sail.

Having thus fully described my invention, I claim as new and desire to secure by Letters 55 Patent—

The support B, formed with diagonally-arranged legs united at the top, in combination with the deflector C, attached to one of the legs and held thereby in inclined position, substantially as and for the purposes described.

ALI MALEKH.
